BOILER AND FURNACE WALL SUPPORT

Glen J. Schoessow, Barberton, Ohio, assignor to
The Babcock & Wilcox Company, Rockleigh,
N. J., a corporation of New Jersey

Application March 14, 1946, Serial No. 654,239

13 Claims. (Cl. 122—235)

1

The invention herein disclosed relates in general to the construction of vapor generating units, and more especially to the supporting structure of steam boilers and furnaces having a fluid cooled combustion chamber laterally adjoining the convection heated boiler surfaces.

An object of my invention is the provision of a support allowing freedom of expansion of essential boiler or furnace parts due to temperature variations.

Another object is the provision of a support arranged to direct all expansive movement from a single restricted location or zone.

An additional object relates to the vertical support of a vertically extended fluid cooled furnace from an intermediate level.

Other objects relate to the lateral support of fluid cooled walls at a given level together with the vertical support of the walls from approximately the same level.

Another object of this invention is the provision of a structural support for a boiler and integral furnace pressure parts which is simple in construction and economical in cost.

The various features of novelty which characterize my invention are pointed out with particularity in the claims annexed to and forming a part of this specification. For a better understanding of the invention, its operating advantages and specific objects attained by its use, reference should be had to the accompanying drawings and descriptive matter in which I have illustrated and described preferred embodiments of my invention.

Of the drawings:

Fig. 1 is a front elevation of a steam boiler setting constituting an embodiment of my invention;

Fig. 2 is a sectional front elevation of the boiler shown in Fig. 1 taken on the line 2—2 of Fig. 4;

Fig. 3 is a plan section of the boiler furnace taken on line 3—3 of Fig. 2;

Fig. 4 is a plan section similar to Fig. 3; taken on line 4—4 of Fig. 2;

Fig. 5 is a vertical section taken on line 5—5 of Fig. 4;

Fig. 6 is a plan view, partly in section, taken on line 6—6 of Fig. 5;

Figs. 7 and 8 are vertical sections taken on lines 7—7 and 8—8, respectively, of Fig. 4;

Fig. 9 is a plan section taken on line 9—9 of Fig. 8;

Fig. 10 is a vertical section taken on line 10—10 of Fig. 3;

2

Fig. 11 is a vertical section taken on line 11—11 of Fig. 10;

Fig. 12 is a fragmentary side elevation taken on line 12—12 of Fig. 3;

Fig. 13 is an end view, partly in section, taken on line 13—13 of Fig. 12;

Fig. 14 is a plan section taken on line 14—14 of Fig. 13;

Fig. 15 is a fragmentary front elevation, partly in section, taken on line 15—15 of Fig. 3;

Fig. 16 is a fragmentary side elevation taken along line 16—16 of Fig. 3;

Fig. 17 is an end view, partly in section, taken along line 17—17 of Fig. 16; and

Fig. 18 is a vertical section taken along line 18—18 of Fig. 3.

In the drawings, and referring first to Figs. 1—4, my invention is shown in connection with a vapor generating unit 10 of the integral furnace type having a setting of substantially rectangular horizontal cross section as defined by upright front and rear walls 12 and 13, respectively, together with oppositely disposed upright side walls 14 and 15, and an upper enclosing wall or roof 16. The space within the setting is divided by an upright interior partition wall 17 to provide a boiler tube space 18 laterally adjoining the upper portion of a furnace or combustion chamber 19 extending downwardly below the level of tube space 18, the lower portion of the chamber being formed as an ash hopper 21 having inclined side wall portions 23 and 24 converging downwardly toward a rectangular throat passage 25 discharging into an ash pit 26 therebelow. In the construction disclosed, the inclined hopper walls 23 and 24 are essentially lower extensions of the upright setting wall 14 and partition wall 17 respectively which thus constitute the side walls of combustion chamber 19. One or more burners 27 of a type suitable for the fuel to be burned are installed in association with the burner opening or openings 28 in front furnace wall 12, for example, to provide a source of heating gases. Air for combustion is supplied to the burner or burners through a windbox 29 to which air under pressure is supplied by the customary forced draft fan (not shown).

The partition wall 17 extends from the front, or burner furnace wall 12 to a location spaced from the rear wall 13 whereby a passage 31 is provided for heating gases flowing from the combustion chamber 19 into the tube space 18. Transverse upright baffles 32 and 34 divide the tube space into serially connected gas passes 35, 36, and 37 through which a substantially horizontal

flow of heating gases is maintained from combustion chamber 19, the spent gases from the final pass 37 being discharged from the setting through breeching 38.

The boiler includes upper and lower drums 39 and 41, respectively, having their longitudinal axes in a common substantially vertical plane, the drums being connected by a main bank of upright boiler tubes 42 disposed within tube space 18 between front and rear walls 12 and 13, such tubes being arranged for example in parallel rows extending longitudinally of drums 39 and 41, and including tubes of different diameters and spacings in different gas passes.

Each of the setting walls 12, 13, 14, and 15, and partition wall 17, comprises at least one row of upright fluid cooling tubes 12a, 13a, 14a, 15a, and 17a, respectively, suitably connected to drums 39 and 41, to provide natural circulation flow paths in parallel with the boiler bank 42. In some instances the connection of the wall tubes to drums 39 and 41 may be direct, as in the case of boiler tubes 42 and wall tubes 12b, 13b, and 15a in the region of tube space 18, whereas in other instances the connections to the drums may be indirect and include known arrangements of headers, make-up tubes and riser tubes as shown. For example, in opposite side walls of the combustion chamber 19, the tubes 14a and 17a are connected at their lower ends to headers 40 to which water is supplied from the lower drum 41 through downcomer means in the form of tubes 43 and 44. In rear wall 13, the tubes 13a are connected at their lower ends to header 50 to which water is supplied from the lower drum 41 through downcomer means in the form of tubes 52. The upper ends of wall tubes 13a are connected to header 53 from which riser tubes 55 extend to the upper drum 39. Similar connections, not shown, are made for tubes 12a in front wall 12. It will be noted from Fig. 4 that the tubes associated with walls 13 and 14 in certain higher temperature zones are more closely spaced than those associated with walls 12 and 15 in lower temperature zones, tubes 13a and 14a being arranged in their respective rows at center-to-center spacings substantially equal to their diameters, and thereby providing an essentially closed wall structure. Where the tubes are spaced apart in the row a space closing refractory wall is provided with the plane of its furnace face tangent to the outer circumference of the tubes.

In hopper wall 24, and in partition wall 17 which forms an upper extension thereof, the tubes 17a are arranged in a single row at center-to-center spacings substantially equal to their diameters as in the case of rear wall tubes 13a and side wall tubes 14a. Tubes 17a are tied together and to lower drum 41 by means of tie bar channel 45 to which each tube is welded top and bottom as at 46, plates 47 welded at intervals to the channel, and plates 48 welded to the drum and to which the plates 47 are secured by suitable fastener means 49.

The portions of tubes 17a above tie bar 45 may be regarded as comprising two groups 17a and 17b as determined by their form and arrangement, in group 17a the tubes extending upwardly in a single longitudinal row to form partition wall 17 including an inclined gas deflecting portion 51, the spacing of tube portions 17a being the same as the spacing of tubes 17a in hopper wall 24, and in group 17b the tubes extending upwardly in spaced relation in a plu-

rality of longitudinal rows across the entrance 31 to gas pass 35.

The entire weight of the boiler including its furnace is carried by a structural frame or foundation support of rectangular horizontal arrangement and comprising, for example, horizontal front, rear, and side frame members 54, 56, and 57, 58, respectively, tied into columns 59 and 61 along opposite sides, the frame members 54, 56 and 58 presenting upper support surfaces in a common horizontal plane. The boiler mud drum 41 is bottom supported, being carried in saddles 62 and 63 supported on a side member 57 which with columns 59 is positioned below drum 41 on a vertical centerline therewith, the saddle 62 being of a fixed type maintaining the drum stationary adjacent burner wall 12 while saddle 63 is of roller supported type permitting longitudinal drum movement relative to its fixed stationary front end portion carried by saddle 62.

The furnace walls are vertically supported at an elevation corresponding substantially to the center line level of the bottom supported boiler mud drum 41, so that all expansion of the entire boiler unit is from that one elevation. Lateral support of the furnace walls is afforded by tie bar and buckstay units 64 and 65 which encompass the furnace, one at the mud drum level and one at a level intermediate the upper and lower boiler drums as indicated in Fig. 1.

In front wall 12, a frame 67 is formed about burner openings 28 comprising upright channel members 68 extending between and suitably secured to front beam 54 and upper lateral support unit 65. The lower support unit 64, although formed in sections 64a and 64b at opposite sides of frame 67, is nevertheless an essentially continuous structure by reason of its attachment as by angles 69 to the upright frame members 68.

At the mud drum level, the lateral support unit 64 comprises tie bars 71 and 72 for front wall 12, and tie bars 73 and 74 for walls 13 and 14, respectively, each tie bar being secured to each wall tube 12a, 13a, or 14a in the associated wall, either direct as in walls 13 and 14, or through channel-section spacers 75 as in wall 12, the tie bars for adjoining walls being welded together at the corners as at 76. In rear wall 13 and in side wall 14, the attachment of tie bars to tubes 13a and 14a is suitably made by welding. In front wall 12 where channel spacers 75 are indicated, tie bar 72 and tubes 12a may, for example, be tied together by means of stud and nut connections as in the embodiment hereinafter described.

The connection of the tubes of wall 15 is correspondingly made with the use of channel spacers. Refractory material as indicated is positioned outwardly of the plane of the outer faces of the tubes and between the spacer channel sections. Buckstays 78, 79, 80 and 81 for the respective walls are secured at intervals therealong to the corresponding tie bars by tie plates 82 and 83 and, for adjoining walls, are interconnected at the corners by horizontally extending gusset plates 84 welded as at 85 top and bottom to the adjacent tie bars 72, 73 and 74. A suitable assembly of buckstay, tie bar and tube is detailed in Fig. 18 where a buckstay 80 for rear wall 13, for example, is shown as comprising upper and lower channel members arranged back-to-back and secured by bolt 89 to a tie plate 82 therebetween having its inner edge welded as at 91 to the upper edge of tie bar 73, the tie plate having a slotted bolt hole 92 therein parallel to the associated wall 13 to permit

relative longitudinal movement between the wall and buckstay.

Each corner plate 84 is provided with two rows of slotted bolt holes 94 and 95 at right angles to each other for receiving bolts or other fasteners 94a and 95a by which the plate is connected to the respective buckstays, the bolt holes in the buckstays being circular and providing normal clearance for the bolts. At the juncture of front wall 12 with side wall 14, for example, the slotted bolt holes 94 are elongated parallel to tie bar 72 in front wall 12, while bolts 94a are in alignment with the centerline of tie bar 74 in side wall 14. Similarly, slotted bolt holes 95 are elongated parallel to tie bar 74 in side wall 14, while bolts 95a are in alignment with the centerline of tie bar 72 in front wall 12. At the juncture of walls 13 and 14, the bolt holes 94, 95 and bolts 94a, 95a are in similar relation with respect to tie bars 73 and 74.

Tie bars 71 and 73 in front and rear walls 12 and 13, together with the corresponding buckstays 78 and 80, are each tied into mud drum 41 as detailed in Figs. 10 and 11 for front wall 12. Angle plate 96 is welded to the drum as shown, and tie bar 71, for example, is secured to the vertical leg of the plate as by bolts 97. Buckstay 78, comprising channel members arranged back-to-back, is secured as by bolts 98 to a tie plate 99 therebetween having its inner edge welded to the upper edge of tie bar 71.

The furnace walls 12, 13 and 14 are vertically supported by pivoted columns 101 extending from foundation frame members 54, 56, and 58 to the lower tie bar and buckstay unit 64 with which the columns have pin connections permitting expansive movement of the walls transversely of the tube lengths therein without inducing a bending reaction in the vertical tube length portions.

Figs. 12, 13 and 14 illustrate two such columns 101 as installed in connection with side wall 14 between foundation frame member 58 and the side wall tie bar 74. Each column is of I-beam cross-section having its bottom end connected by a pin 102 to upstanding flanges of angles 103 mounted at opposite sides of its web 104 on a suitable footing or base plate 105. At the upper end of column 101 a portion of flange 106 is cut away to receive plates 107 secured as by welding to opposite sides of the column web and extending toward the row of tubes 14a where they are connected by pin 108 to horizontally spaced plates 109 welded to tie bar 74 throughout its width and suitably to tie plate 83 at its upper end. When located adjacent burner wall 12 as indicated, where longitudinal wall displacement is the least, the two columns 101 may be connected by a diagonal brace 112 for increased wall rigidity, the brace being framed into the vertical columns 101 and having its web 113 welded thereto. Figs. 16 and 17 show columns 101 as previously described but without the diagonal bracing, as used at other positions in wall 14, or in other walls, or at locations as in front wall 12 where a single column 101 is indicated.

The lateral support unit 64 and the pivoted support connections to tie bar components of that unit are at substantially the same level as the center line of the lower drum of the boiler proper, and provision is thus made for all expansion and contraction to take place from such a predetermined level and from the fixed end of that drum.

This is accomplished through the double pinning of the columns in their connections to the supporting steel work and to the tie bars. The

pivoted columns will tip or change their upright alignment with changes in the amount of movement of the point of wall attachment. For the rear wall 13 the slight movement will be angularly about the axes of the lower pivoted connections while in the case of the side wall 14 the movement of the upper pivoted connection will be both outward and in a direction parallel to the plane of the wall. To provide for the latter movement the pin connections are provided with some clearance between pins and holes.

The pin type of connections for the column have been selected as a type well adapted to fabrication and erection, but other specific pivot type constructions permitting similar relative movement of the column relative to its supporting base and relative to the member supported at the top of the column, as for example ball and socket connections, are within the scope of the invention.

The tie bar and buckstay unit 65 at the upper level between drums 39 and 41 is of the same general construction as unit 64 except that it is continuous about the entire upper cross section of the setting and is supported solely by tubes adjacent the walls.

In front wall 12, because of the smaller thickness of refractory 117 adjacent tube space 18, the channel spacers 118 may be of smaller size requiring tie bars 119 and 121 to be offset and connected as at 123. In rear wall 13, the tie bars 124 and 125 are also offset and connected as at 126, in this wall tie bar 124 being secured to tubes 13b with spacers 118 therebetween, while tie bar 125 is secured to tubes 13a direct. In side wall 14 tie bar 126 is secured direct to tubes 14a, whereas in the opposite side wall 15, tie bar 127 is secured to tubes 15a with spacers 118 therebetween.

Buckstays 132, 133, 134, and 135 for walls 12, 13, 14, and 15 respectively are each formed of channel members arranged back-to-back and tied in to the respective tie bars by tie clips 136 and 137 of angular formation as in Figs. 5-7, each clip having a slotted bolt hole 92 therein to allow for differential expansive movement between the associated tie bars and buckstays. Referring to Figs. 5 and 6 where channel spacers are employed, the horizontal leg of clip 136 extends between the channels of buckstay 133 to which it is secured by bolt 138, while the vertical leg extends upwardly against the outer side of tie bar 124 to which it is secured by threaded studs 139 welded to tube 13b and fitted with nuts 141, the studs extending through channel spacers 118, and a pipe spacer 142 being interposed between clip 136 and spacer 118 to bridge the gap above tie bar 124. Referring to Fig. 7 where channel spacers are omitted, tie bar 125 is bolted direct to the tube, and pipe spacer 142 is inserted between clip 137 and tube 13b. At locations along the various walls where no clip members are indicated, the same constructions shown in Figs. 5-7 may be employed, merely by omitting clip 136 or 137.

The tie bars in adjoining walls are welded together at all four corners 76 as in the construction at two corners for tie bars at the mud drum level. Buckstays in adjoining walls are also interconnected at the four corners, in the manner shown in Fig. 3 for two corners, with bolt holes 94, 95 and bolts 94a, 95a, arranged as previously described, for attachment to gusset plates 84 which are welded to the tie bars at 85.

Tie bars 145 are included in the assembly of

partition wall 17 as indicated in Figs. 4, 8 and 9, such bars extending transversely of tubes 17a suitably in overlapping sections at adjacent levels, intermediate the height of the partition, as indicated in Fig. 8. Tube 17c nearest the front wall tie bar 121 is tied thereto by stud and nut connections as in Fig. 5, and all tubes of the partition including tube 17c are tied to bars 145 in a similar manner with studs 146 and nuts 147 as indicated. Each tie bar 145 is of corrugated cross section providing alternate ridges and grooves for close engagement with the tube surfaces. The bar or bar section 145 nearest front wall 12 is extended as at 148 for attachment by bolts 149 to channel spacer 175.

The described supporting provisions for the walls and pressure parts of a vapor generating unit are of simple and relatively low cost construction, requiring substantially less steelwork than prior commercial constructions for this purpose, and yet more effectively providing the necessary freedom of movement of the supported parts due to thermal expansion and contraction and thus avoiding distortion and possible rupture of the parts so stressed. In one type of steam boiler, for example, the amount of supporting steelwork was reduced approximately 50%.

While in accordance with the provisions of the statutes I have illustrated and described herein the best forms of my invention now known to me those skilled in the art will understand that changes may be made in the form of the apparatus disclosed without departing from the spirit of the invention covered by my claims, and that certain features of my invention may sometimes be used to advantage without a corresponding use of other features.

I claim:

1. A vapor generating unit comprising a vertically arranged bank of generating tubes, upper and lower horizontally extending drums connected to said tubes, means for bottom-supporting said drums and tube bank, a laterally offset furnace combustion chamber at one side of said tube bank and having upright boundary walls lined with upright generating tubes, said walls including a pair of opposing walls extending substantially parallel to said drums and having the tubes thereof extending to and connected to said upper drum, said opposing walls and the wall tubes thereof having integral inclined lower portions converging downwardly at elevations below said lower drum, and means for vertically supporting said boundary walls including weight support means engaging said opposing wall tubes above said inclined lower portions at approximately the elevation of said lower drum, said weight support means including means securing the tubes of one of said opposing walls to said bottom-supported lower drum.

2. A furnace having a boundary wall including a row of upright fluid heating tubes, horizontally arranged bar means secured to and supported on said tubes and tying the tubes in predetermined center-to-center relation at a level intermediate their height, upright weight support means having an end portion pivotally connected to said tying bar means, a load carrying structure positioned externally of said wall and adjacent thereto, and a pivoted connection between the opposite end portion of said support means and said structure, said pivotal connections providing parallel pivotal axes arranged parallel to said row of tubes to permit movement of said tubes in a direction normal to said wall.

3. A furnace having a boundary wall including a row of upright fluid heating tubes, horizontally arranged bar means secured to and supported on said tubes and tying the tubes in predetermined center-to-center relation at a level intermediate their height, upright weight support means having an upper end portion pivotally connected to said tying bar means, a load carrying structure positioned externally of said wall and adjacent thereto, and a pivoted connection between a lower end portion of said support means and said structure, said pivotal connection providing parallel pivotal axes arranged transversely of said tubes to permit movement of said tubes in a plane normal to said wall.

4. A furnace having vertical boundary walls defining a combustion chamber of substantially rectangular horizontal cross-section, a row of vertical fluid heating tubes extending along the inner side of each of said walls, a horizontally arranged tie bar connected to each row of tubes, a gusset plate fixedly secured to the adjoining ends of tie bars in adjoining walls, a horizontally arranged buckstay extending along the outer side of each of said adjoining walls and having a web portion overlapping said gusset plate, means vertically supporting each of said buckstays on tubes of the corresponding wall comprising a weight supporting connection between each tie bar and the corresponding buckstay and permitting relative longitudinal movement therebetween, and means forming expandable connections between the ends of adjoining buckstays and said gusset plate comprising connecting members extending through registering holes in said gusset plate and overlapping web portions.

5. A furnace having vertical boundary walls defining a combustion chamber of substantially rectangular horizontal cross-section, a row of vertical fluid heating tubes extending along the inner side of each of said walls, a horizontally arranged tie bar connected to each row of tubes, a gusset plate fixedly secured to the adjoining ends of tie bars in adjoining walls, a horizontally arranged buckstay extending along the outer side of each of said adjoining walls, means vertically supporting each of said buckstays on tubes of the corresponding wall comprising a weight supporting connection between each tie bar and the corresponding buckstay and permitting relative longitudinal movement therebetween, means forming expandable connections between the ends of adjoining buckstays and said gusset plate, and means vertically supporting said walls comprising longitudinally spaced upright supports pivotally connected to each of said tie bars about a common horizontal axis parallel thereto.

6. A furnace wall including a row of vertically extending fluid heating tubes, a horizontally extending tie bar welded to the outer sides of said tubes, a buckstay laterally supporting said wall and comprising a pair of horizontally arranged spaced channel bars positioned with their web portions back to back, means for supporting said buckstay on said tubes comprising a plate positioned between said channel bars and connected to the web portions thereof, said plate having a portion projecting inwardly beyond said channel bars and secured to said tie bar, and means for vertically supporting said wall inclusive of said buckstay comprising weight support means having a pivoted connection with said tie bar.

7. In a vapor generating unit having an upper and a lower drum arranged in substantially vertical alignment and connected by tubes, means

for bottom-supporting said drums and said tubes, a furnace combustion chamber arranged laterally of and directly adjacent the space containing said tubes and having an inner and an outer upright wall respectively adjacent to and remote from said lower drum, each of said walls comprising a row of upright fluid cooling tubes having circulatory connections with said drums, said inner wall including tubes extending to and connected to said upper drum, said walls and the tubes thereof having substantially vertical portions at substantially the elevation of said lower drum and having integral inclined lower portions converging downwardly at elevations below said lower drum, and means for vertically supporting said walls comprising weight support means engaging said vertical tube portions in each of said walls at an elevation corresponding substantially to the elevation of said lower drums, inclusive of means maintaining the tubes of said inner wall stationary with respect to said lower drum in the region of weight support means in engagement with said inner wall tubes.

8. A furnace having a pair of adjoining upright walls defining a corner of a furnace combustion chamber a row of vertically arranged fluid heating tubes extending along each of said walls adjacent the inner side thereof, a horizontally arranged tie bar connected to each row of tubes, horizontally arranged buckstays extending respectively along the outer sides of said walls and formed with horizontally extending web portions adjacent said corner, means including said tie bars vertically supporting said buckstays on tubes of the respective walls, a corner plate overlapping said web portions and fixedly secured to the tie bars in said walls, and means forming horizontally expandable connections between said corner plate and said web portions comprising members extending through registering holes in said overlapping corner plate and web portions, said holes in web portions of the respective buckstays being aligned in sets with tie bars in the respective adjoining walls, and the holes in said corner plate being arranged in sets each registering with a set of said aligned holes and being elongated transversely of the direction of said alignment.

9. A vapor generating unit comprising a vertically arranged bank of generating tubes, an upper and a lower horizontally extending drum connected to said tubes, means for bottom-supporting said lower drum and through said tube bank vertically supporting said upper drum, a laterally offset furnace combustion chamber at one side of said tube bank and having vertical boundary walls lined with vertical generating tubes discharging to said upper drum, means for vertically supporting said wall tubes intermediate the lengths thereof at approximately the elevation of said lower drum, said wall tube supporting means including a stationary structure externally of said furnace chamber and pivoted support connections between said structure and tubes of the respective walls, and downcomer means connecting said lower drum to the lower ends of said wall tubes.

10. A vapor generating unit comprising a vertically arranged bank of generating tubes, an upper and a lower horizontally extending drum connected to said tubes at upper and lower ends thereof, means for bottom-supporting said lower drum and through said tube bank vertically supporting said upper drum, a laterally offset furnace combustion chamber at one side of said tube bank and having vertical boundary walls lined with vertical generating tubes, means for vertically

supporting said wall tubes at approximately the elevation of the center line of said lower drum including upright column members externally of and adjacent to said wall tubes, pivoted support connections between said column members and said wall tubes, and means extending transversely of said wall tubes and connected thereto and to said lower drum for laterally supporting said walls at approximately said elevation of bottom support.

11. A vapor generating unit comprising a vertically arranged bank of generating tubes, an upper and a lower horizontally extending drum connected to said tubes at upper and lower ends thereof, means for bottom-supporting said lower drum and through said tube bank vertically supporting said upper drum, a laterally offset furnace combustion chamber at one side of said tube bank and having vertical boundary walls disposed in separate planes and lined with vertical generating wall tubes discharging to said upper drum, means for laterally supporting said walls at a substantially common elevation, means for vertically supporting said walls including upright column members externally of and adjacent to said wall tubes, and means including pivoted vertical support members connecting said column members to said wall tubes at approximately said elevation of lateral support.

12. A vapor generating unit comprising a bank of upright generating tubes, an upper and a lower horizontally extending drum to which opposite ends of said tubes are connected, means for bottom-supporting said lower drum and through said tube bank providing vertical support for said upper drum, a furnace combustion chamber arranged laterally of and adjacent said tube bank and having an inner and an outer upright wall paralleling said lower drum and arranged respectively adjacent to and remote from said lower drum, each of said walls comprising upright fluid conducting tubes extending to elevations above said lower drum and having circulatory connections with said drums, said walls and the tubes thereof having substantially vertical portions at substantially the elevation of said lower drum and having integral inclined lower portions converging downwardly at elevations below said lower drum, and means for vertically supporting said walls comprising weight support means engaging said vertical tube portions in each of said walls while maintaining said vertical portions of tubes of said inner wall stationary with respect to said lower drum.

13. A vapor generating unit comprising a vertically arranged bank of generating tubes, an upper and a lower horizontally extending drum connected to said tubes at upper and lower ends thereof, means for bottom-supporting said lower drum and through said tube bank vertically supporting said upper drum, a furnace combustion chamber arranged laterally of and adjacent one side of said tube bank and having upright boundary walls disposed in separate planes, said walls including upright wall cooling tubes extending to elevations above said lower drum and having circulatory connections with said drums, one of said boundary walls constituting a wall arranged transversely with respect to said lower drum, means for laterally supporting said walls at a substantially common elevation, means for vertically supporting said walls including an upright column member externally of and adjacent to wall tubes associated with said transversely arranged wall, and means including a pivoted vertical support member connecting said column

11

member to said wall tubes of said transversely arranged wall at approximately said elevation of lateral support.
